UNITED STATES PATENT OFFICE.

WALTER L. HAMILTON, OF HOLYOKE, MASSACHUSETTS, ASSIGNEE TO B. F. PERKINS & SON, INC., OF HOLYOKE, MASSACHUSETTS, A CORPORATION OF MASSACHUSETTS.

DYNAMOMETER.

1,233,269.

Specification of Letters Patent. Patented July 10, 1917.

Application filed August 14, 1916. Serial No. 114,778.

To all whom it may concern:

Be it known that I, WALTER L. HAMILTON, a citizen of the United States of America, residing in the city of Holyoke, county of 5 Hampden, and State of Massachusetts, have invented certain new and useful Improvements in Dynamometers, of which the following is a specification.

This invention relates to improvements in 10 dynamometers and more particularly to an advantageous arrangement of indicating mechanism for dynamometers of the so-called "spiral spring" type.

An object of the invention is to provide 15 in a dynamometer having driving and driven elements connected by a resilient means, means to indicate the relative movement between said elements which mechanism is arranged to be positively moved in 20 both directions by said relative movement in an improved manner, the construction being characterized by uniform increments of movement of the indicating mechanism for uniform increments of load upon the driven 25 element and by moving the indicating means by said relative movement with a minimum amount of effort.

Another object of the invention is to provide 30 an improved dynamometer having driving and driven elements in line with one another, the former arranged to drive the latter through the intermediary of a resilient connection, and means to indicate by the relative movement between said elements 35 the tension of said connection and thus the load on said driven element.

A further object of the invention is to provide 40 a dynamometer of generally simplified and improved mechanical structure.

Other objects and advantages will appear 45 in the description to follow and in the annexed claims.

For the purpose of illustrating one manner 50 in which the invention may be applied 45 in practice, a preferred embodiment thereof, with detailed variations, is shown in the accompanying drawings, in which—

Figure 1 is a top plan view of the dynamometer;

Fig. 2 is a sectional elevation taken on the 55 line 2—2 of Fig. 1;

Figs. 3 and 4 are cross sectional views

taken on the lines 3—3 and 4—4, respectively, of Fig. 1;

Fig. 5 is a fragmentary plan view showing 55 a modification in the indicating mechanism;

Fig. 6 is a partial plan view showing a modification in the arrangement of parts of the dynamometer; and

Fig. 7 is a cross sectional view taken on the 60 line 7—7 of Fig. 6.

Referring to these drawings in detail and particularly to Figs. 1 to 4; a shaft 10, having a driving pulley 11 keyed thereto, is rotatably mounted at one end in the right hand 65 one of a set of bearings *a* which are secured as shown in Figs. 1 and 2 to a base *b*. Shaft 10 has a portion 11 of reduced diameter and another portion 12 which is of less diameter than the portion 11. Rotatably 70 mounted on the latter is a sleeve 13 which is mounted in the left-hand pair of bearings *a* and thereby supports the other end of shaft 10. Fixed to sleeve 13, as shown in Fig. 2, is a pulley 14 which is adapted to 75 drive the machine to be tested by the dynamometer. Fixed to sleeve 13 is a cup-shaped member 15 and secured to shaft 10 is a sleeve 16 which extends within member 15 and is connected to the inner periphery thereof by 80 a spiral spring 17, as best shown in Fig. 4. It will thus be seen that shaft 10 and sleeve 13 are connected by resilient means so that, if power is applied to pulley 11, a machine belted to pulley 14 will be driven through 85 the intermediary of the spring. Furthermore, the spring 17 will be wound up to some extent so that there will be a relative rotation of shaft 10 and sleeve 13 and the amount of this rotation will be a measure of 90 the power required to drive the machine connected to pulley 14 in a now well understood manner.

The means for indicating the relative 95 turning movements between shaft 10 and sleeve 13 will now be described. Fixed to sleeve 13 is a drum 18 and fixed to the portion 11 adjacent the drum is an arm 19 which extends on either side of member 11, as shown in Fig. 2. Secured to the upper and 100 lower extremities of arm 19 are pulleys 20 and 21 and to opposite faces of arm 19 adjacent the member 11 are secured other pulleys 22 and 23, respectively. Slidable on

member 12 is a disk 24 which is movable adjacent a graduated scale 25 fixed to a suitable bracket *e* on base *b*. Disk 24 is arranged to be propelled back and forth on member 12 by means of a cord 26, both ends of which are connected to the drum at 27. Starting with one end from the point 27, the cord passes over the periphery of drum 18, downwardly around pulley 21, upwardly over pulley 22, then horizontally to the left in parallel relation with member 12, and loosely through a hole 28 (Fig. 3) in disk 24 to and around a pulley 29 fixed on the end of member 12. The cord then passes horizontally to the right, is looped through two holes 30 (Fig. 3) in disk 24, and continuing passes under pulley 23, then upwardly over pulley 20, and thereafter downwardly, being wound around the drum in an opposite direction to the first end of the cord and secured to the drum at 27. It will be evident that as drum 18 turns relatively to arm 19 the cord 26 will be wound up at one end and unwound at the other end, and by the looped connection with holes 30 will positively move the disk 24 in both directions.

The arrangement described is important since the disk 24 is movable with a minimum of friction. Movable measuring elements have been provided which are positively moved in one direction but are provided with springs or the like to secure the return movement. The present construction avoids the necessity for a spring and eliminates the friction loss incident to the use of the spring. Furthermore, by dispensing with the spring the scale 25 may be uniformly graduated as against the non-uniform graduations obtained when a spring is employed. It is particularly to be noted that the dynamometer described may readily be made to secure as close accuracy as may be desired simply by elongating the member 12 and increasing the diameter of drum 18.

If desirable, the dynamometer may be provided with a recording mechanism, as shown in Fig. 5, so that a continuous and permanent record of the power used by a particular machine may be obtained. Fixed in and extending between spaced brackets *d* secured to base *b* is a rod 31 upon which a member 32 is slidable. The latter carries a suitable marking pen 33 and is engaged by disk 24, as shown, so that as the latter moves on part 12 the pen 33 is moved horizontally across a record sheet 34 which is propelled uniformly by a suitable clock mechanism *e*. The curve 35 traced on sheet 34 thus represents power plotted against time and gives a continuous record of the power consumption of the machine tested.

Where the dynamometer is used for testing machines already in place in factories, I provide a modified arrangement of parts 65 which is illustrated in Figs. 6 and 7. For

such use, it is desirable to have the driving and driven pulleys directly in line with one another, since then the dynamometer may be simply interposed between the main drive shaft and the machine to be tested without 70 the necessity (if the arrangement shown in Fig. 1 is used) of fastening an additional pulley on the main driving shaft or moving the machine to be tested. The driving pulley 11 is replaced by a spur gear 37 which 75 meshes with a similar gear 38 on a counter-shaft 39 rotatably supported in bearings *f* secured to base *b*. The driving pulley 11 is fixed to shaft 39 directly behind pulley 14.

In operation, power is applied to pulley 80 11 and the machine to be tested is connected to pulley 14. The spring 17 is wound up until its tension just balances the load on the machine to be tested after which the machine is driven just as if the shaft 10 and sleeve 13 were rigidly connected. The relative turning movement between the shaft 10 and sleeve 13 causes the disk 24 to move axially along the member as already described and the extent of such movement, as 85 indicated on scale 25, is a measure of the power consumption of the machine tested. Obviously, the pulley 11 may be the driven, and pulley 14 the driving members, but the described arrangement is preferred since by 90 having the driven pulley nearest the indicating mechanism, the friction losses of the dynamometer are not included in the reading on scale 25 or curve 35.

The invention has been described in a 100 preferred form with detailed variations for illustrative purposes, but the scope of the invention is defined by the appended claims rather than by the foregoing description.

What I claim is—

1. A dynamometer, comprising, a driving element, a driven element, a resilient connection between said elements arranged by its tension to balance the load on the driven element, a slideable indicator, and flexible 110 means connecting the driving and driven elements and said indicator, said means being operable by the relative movement between said elements to positively move said indicator in both directions to indicate the 115 load on the driven element.

2. A dynamometer, comprising, a driving shaft, a sleeve rotatable thereon, a load driving member on the sleeve, a resilient means connecting the sleeve and shaft, an indicator 120 slideable axially on the latter, a drum on the sleeve, and flexible means connecting the drum and indicator to positively propel the latter back and forth upon the shaft to indicate by its movement the tension of said 125 spring and thus the load on said member.

3. A dynamometer, comprising, a driving shaft, a driven shaft, driving members on said shafts arranged in the same plane, a resilient device connecting said shafts ar- 130

ranged to be placed under tension and by its tension to balance the load on the driven shaft, and means operable by the relative turning movement between the shafts to indicate the load upon the driven shaft.

4. A dynamometer, comprising, a driving shaft, a sleeve rotatable thereon, a resilient means connecting the sleeve and shaft, a drum on the sleeve, an arm on the shaft adjacent the drum, pulleys on said arm, a pulley on the end of the shaft at a distance from said arm, a flexible belt looped around the

last named pulley and extending to and over the first-named pulleys, the ends of said belt being wound around said drum in opposite directions and secured thereto, and an indicator slidable on the shaft between the arm and last-named pulley and connected to said belt, whereby the indicator may be moved positively in both directions by the relative movement between the shaft and sleeve.

15. 20. WALTER L. HAMILTON.
